SOAP DISPENSING BACK SCRUBBING
BRUSH

Flora H. Ellinger, Milwaukee, Wis.

Application June 7, 1946, Serial No. 675,132

4 Claims. (Cl. 15—122)

My present invention relates generally to improvements in brushes, and relates more particularly to improvements in the construction and operation of back scrubbing brushes.

A primary object of the present invention is to provide a new and useful improved brush which is simple in construction and highly efficient in use, and which is especially adapted for scrubbing the back of a bather.

A more specific object of this invention is to provide an improved back scrubbing brush which is highly flexible and readily manipulatable for effective cleansing.

Another specific object of my invention is to provide an improved double-handled brush which may be conveniently gripped and manipulated to thoroughly scrub the user's back while bathing, and which is moreover free of protruding parts likely to scratch or otherwise mar the user's skin.

Another specific object of the present invention is to provide an improved sanitary back scrubbing brush which is adapted to roll over and gently knead the skin of the user during operation thereof.

Another specific object of the present invention is to provide an improved back scrubbing brush which may be quickly and conveniently provided with a novel and efficient soap supplying instrumentality.

An additional specific object of this invention is to provide an improved back scrubbing brush in which a uniform amount of wear is given during use to all of the bristles, and which may be readily provided with a removable and replaceable supply of soap adapted to be evenly distributed over the skin area being scrubbed during use of the brush.

A further specific object of my invention is to provide an improved back scrubbing brush adapted to receive a novel soap carrying and distributing strip which may be readily merchandised for replacement at low cost.

Still another specific object of my present invention is to provide an improved sanitary back scrubbing brush which is sturdy in construction, and which may be readily manufactured of relatively few standard and available materials at moderate cost.

These and other specific objects and advantages of the present invention will be apparent from the following detailed description.

A clear conception of the several features constituting my present improvement, and of the mode of constructing and of utilizing brush as-

semblages built in accordance with my invention, may be had by referred to the drawing accompanying and forming a part of this specification wherein like reference characters designate the same or similar parts in the several views.

Fig. 1 is a plan view of the improved brush assemblage;

Fig. 2 is an enlarged transverse section through the brush, taken along the line 2—2 of Fig. 1;

Fig. 3 is a similarly enlarged longitudinal section through the brush;

Fig. 4 is a similarly enlarged end view of the brush;

Fig. 5 is a similarly enlarged plan view of a soap carrier especially adapted for use with the improved brush, a portion of the wall being broken away to reveal the contents thereof; and

Fig. 6 is a somewhat diagrammatic plan view of a modified brush assemblage.

While the invention has been shown and described herein as being applied to a brush assemblage especially adapted for back scrubbing and cleansing purposes, it is not my desire or intention to thereby unnecessarily restrict the scope or utility of the improvement.

Referring to the drawing, the improved brush assemblage comprises, in general, an elongated cylindrical brush 10 consisting of a tubular carrier 11 having a multiplicity of outwardly projecting bristles 12 formed thereon in a helical series, the carrier 11 being provided with a central axial opening 13 therethrough; a relatively flexible tube 14 extending through the central opening 13 of the carrier 11, the opposite ends of the tube 14 projecting a substantial distance beyond the ends of the carrier and being bent to an approximate U-shape to provide arms 15; and a gripping handle 16 secured in any suitable manner to the free end of each arm 15. The bristles 12 may be attached to the carrier 11 in any known manner, as by water resistant adhesives or rubber cement, and one or more series or helical rows of bristles may be provided as desired. The tubing 14 should be relatively flexible for easy adjustment, and with the carrier 11 rotatably supported on a medial portion of the tube 14, the projecting ends of this tube may be readily bent without special tools to form the arms 15. If it is desired to positively limit axial movement of the carrier 11 on the tube 14, stops may be provided at the desired points on tube, and these limit stops may consist merely of beads of solder, weld deposits, or annular shoulders fixed to the tube 14.

To furnish soap to the cleansing area during

use of the brush, an elongated flexible tube or jacket 17 of porous material such as cheese-cloth closed at the ends by stitching 18 or the like and housing a supply of soap chips or flakes 19 is provided. The soap-containing tube 17 may be conveniently secured to the carrier 11 by means of spring clips 20, as shown, or in any other suitable manner, and is wound helically about the carrier body in the channel formed between the bristles 12. Obviously, the brush 10 may be used either with or without the soap-containing tube 17 which may be readily applied by first clamping one end to the carrier 11 by means of one of the spring clips 20, then winding the tube 17 around the carrier 11 between the bristles 12, and finally clamping the other end to the carrier 11 by means of the other spring clip 20, and which may likewise be quickly removed by following the reverse procedure. The soap containers 17 may be manufactured in large quantities and sold at low cost, and the exhausted containers may therefore be discarded and replaced.

After assembly and during normal use of the improved brush, the user may grip the handles 16 in the most convenient and natural manner preparatory to use for back-scrubbing purposes; and because of the relative flexibility of the tube 14 forming the arms 15, the device will more or less adjust itself automatically to the most desirable formation suitable for its intended purpose during the back-scrubbing operation. The brush may be operated from any one of several positions, the most common being as follows: from an approximately vertical position with the handles held above the bather's shoulders and pointed downwardly and somewhat rearwardly; from an approximately horizontal position with the arms 15 bowed and with the handles 16 held in front of the bather's body and pointed either upwardly or downwardly in the most natural manner; from an approximately horizontal position with the arms 15 extended approximately in an axial direction with respect to the brush and with the handles held laterally of the bather's body; or from an approximately vertical position with the handles in a lowermost position and pointed upwardly and somewhat rearwardly. As the brush 10 is moved over the wet back of the user, the water and agitation causes the soap 19 in the porous jacket 17 to lather and effectively cleanse, by the combined action of the soap and brush, the user's back. During this movement of the brush over the bather's back, the carrier 11 also revolves to some extent, thereby gently massaging the back of the bather during cleansing thereof and causing uniform wear on substantially all of the bristles 12.

From the foregoing detailed description, it is apparent that my present invention provides an improved back scrubbing brush which is simple and durable in construction, and which is moreover highly efficient and flexible in actual use. The improved brush assemblage is composed of relatively few parts which are of standard and available stock; and in addition to being readily and conveniently manipulatable from various positions, the assemblage is neat and compact in appearance. The assemblage may obviously be manufactured of various suitable materials, and is sanitary and free of protruding parts which would be likely to mar the user's skin. The device may be assembled by a novice and may consequently be merchandised either in assembled

or dismantled condition, and the soap containing units may be readily replaced at low cost as the soap supply is exhausted therefrom. By virtue of the rotating action of the brush in operation, the bather's skin is given a highly desirable and pleasant treatment during cleansing and the bristles are subjected to minimum and uniform wear.

While the improved brush assemblage has been specifically shown and described herein as comprising a back scrubbing brush having a multiplicity of bristles secured to the carrying member in a helical series and with the soap containing tube wound helically about the carrier between the bristles, the brush may obviously be utilized for other than back-scrubbing purposes, and the bristles may be secured to the carrier in any manner so as to provide intervening channels for renewable insertion and attachment of the soap carrying strips.

A particularly desirable feature of the improved device is the flexibility of the arms which permit almost universal adjustment of the assemblage to suit the convenience of the individual user; and in Fig. 6 I have shown a somewhat modified structure wherein the handles are omitted with the arms 15' bent to form a substantially elliptical gripping member. In this modified assemblage, the arms are preferably held together at the ends thereof by means of a clamp 21 which may be readily removed if desired; and in actual use, the arms 15' surround the bather's body and the brush may be manipulated by gripping the arms 15' at any convenient point.

It should be understood that it is not desired to limit this invention to the exact details of construction, or to the precise mode of use, herein shown and described, for various modifications within the scope of the appended claims may occur to persons skilled in the art to which this invention pertains.

I claim:

1. A back scrubbing brush assemblage comprising, an elongated carrier having outwardly projecting bristles formed thereon in a helical series, said carrier having a longitudinal opening therethrough, a member extending through the opening of said carrier and projecting beyond the ends thereof to form arms, gripping means at the end of each arm, and a soap containing member wound helically about and secured to the carrier between said bristles.

2. A back scrubbing brush assemblage comprising, an elongated carrier having outwardly projecting bristles formed thereon in a helical series, said carrier having a longitudinal opening therethrough, a member extending through the opening of said carrier and projecting beyond the ends thereof to form arms, gripping means at the end of each arm, a soap containing member wound helically about the carrier between said bristles, and means cooperating with said soap containing member and with said carrier for retaining said soap containing member in position on said carrier.

3. A back scrubbing brush assemblage comprising, an elongated carrier having outwardly projecting bristles formed thereon in a helical series, an arm extending from each end of said carrier, gripping means at the free end of each of said arms, and a soap containing member wound helically about and detachably secured to the carrier between said bristles.

4. A back scrubbing brush assemblage comprising, an elongated carrier having outwardly

projecting bristles formed thereon in a helical series, an arm extending from each end of said carrier, gripping means at the free end of each of said arms, a soap containing member wound helically about the carrier between said bristles, and means cooperating with said soap containing member and with said carrier for retaining said soap containing member in position on said carrier.
